THOMAS E. LAYDEN, OF TOPEKA, KANSAS.

EXHAUST PIPE.

Application filed November 22, 1924. Serial No. 751,536.

My invention relates to exhaust pipes more particularly for use in connection with locomotive boilers and cylinders; and the invention has for its object the provision of 55
 6 an exhaust pipe which will eliminate all possibility of the exhaust steam "backing up" into the exhaust passages leading from the opposite steam-chests and cylinders of the locomotive; namely a construction 60
 10 which will prevent the possibility of back pressure being created in the opposite cylinders of the locomotive or engine.

The invention also has for its object the provision of an exhaust pipe which, aside 15 from preventing the creation of back pressure, will at the same time discharge the exhaust steam in such manner, relative to the smoke stack, as to properly fill the stack to create sufficient draught so as to enable 20 the boiler to produce the amount of steam necessary to operate the locomotive efficiently and to greater capacity.

The above enumerated objects and advantages, as well as other objects and advantages inherent in the construction, will all be more fully comprehended from the following detailed description of the accompanying drawings, wherein:—

30 Figure 1 is a transverse sectional view of the front or smoke box end of a locomotive with my improved exhaust pipe in position.

35 Figure 2 is a longitudinal sectional view of the front or smoke box end of the locomotive, with the steam chests and cylinders omitted, and my improved exhaust pipe shown in side elevation.

40 Figure 3 is a detailed vertical sectional view taken on the line 3—3 of Figure 2 looking in the direction of the arrows.

45 Figure 4 is a detail sectional view taken on the offset line 4—4 of Figure 3 looking in the direction of the arrows.

Figure 5 is a cross sectional view taken 50 on the line 5—5 of Figure 4 looking downwardly.

Figure 6 is a cross sectional view taken on the line 6—6 of Figure 4 looking in the direction of the arrows.

55 Figure 7 is a across sectional view taken on the line 7—7 of Figure 4 looking in the direction of the arrows.

Figure 8 is a cross sectional view taken on the line 8—8 of Figure 4 looking downwardly.

Figure 9 is a perspective view of the exhaust pipe tip, with portions broken away to show the internal construction.

55 My improved exhaust pipe is designed to permit a complete and easy exhaustion of the exhaust steam from the respective cylinders, or rather the steam chests of the cylinders, without, however, permitting the exhaust steam from the exhaust channels of the cylinder on one side of the locomotive to "back up" into the exhaust passages from 60 the steam chest or cylinder on the opposite side of the locomotive, while at the same time conducting the exhaust steam centrally and completely through the smoke stack of the locomotive so as to create sufficient 65 draught whereby steam in the boiler may be quickly obtained and therefore enable the locomotive to operate more efficiently and to a greater capacity.

70 The specific exemplification of the invention as disclosed in the drawings comprises the exhaust pipe generally indicated at 15 which is preferably provided at its bottom with a flange 16 whereby the exhaust pipe may be bolted or suitably secured to the 75 cylinder saddle indicated at 17; the cylinder saddle being provided with the usual exhaust channels 18 and 19 which communicate with the valve-chambers or steam-chests 80 20 and 21, respectively, and which in turn 85 communicate by the usual valved ports with the cylinders 22 and 23, respectively.

85 The exhaust pipe 15 is provided in the lower end with a substantially centrally located short vertical partition or wall 24 90 extending transversely of the exhaust pipe and terminating in an upwardly sloping portion 25 which extends toward and constitutes a portion of one of the side walls of the exhaust pipe as shown in Figures 3 and 95 7. The wall portions 24, 25 provide a substantially rectangular steam passage 26 at the bottom of the pipe (see Figure 5) which (in the particular illustration) communicates with the steam channel 18. This steam 100 passage 26 in the upper part of the exhaust pipe extends transversely throughout the width of the exhaust pipe at a point beneath the exhaust pipe tip 27. The upwardly sloping portion 25 is disposed intermediate of and also formed integral with the curved and sloping partitions 28, 28 which flare into the oppositely curved portions 29, 29

100

105

which extend transversely of the wall portion 24 and unite at one side of the pipe to constitute one of the outer side walls as shown at 29^a in Figure 7. These curved 5 portions 29, 29 are in spaced relation and thus provide exhaust passage 26 with an hour-glass formation, see Figure 7.

Extending upward in a sloping manner from the wall portion 24 and on both sides 10 of the partitions 29, 29 and in reality constituting a continuation of the partitions 28, 28 are the portions 28^a, 28^a, which extend substantially at right angles to the portions 29, 29. These portions 28^a, 28^a, which 15 extend up from wall portion 24 are integral with the two outer side walls 30, 30 which unite with an outer side wall 31. This side wall 31, which partially slopes inwardly, is partially intersected by the sloping partition 25 as shown in Figure 7.

The wall and partition formation described provide the lower part of the exhaust pipe with the exhaust passage 32 which is disposed substantially parallel with the 25 bottom of the passage 26 and of substantially equal dimensions therewith, as more clearly shown in Figure 5.

As shown in Figure 7, the various outer walls and partitions, all of which are integral with each other and emanate from the rectangular wall formation shown in Figure 5, cause the exhaust passage 32 to be divided into the two passages 33, 33, on opposite sides of the exhaust passage 26, see 35 Figure 7.

The various outer walls and partitions all unite with the apertured top wall or partition 34, see Figure 8: the top wall having openings corresponding with the various 40 exhaust passages previously described; and the top is preferably extended beyond the side walls to provide an attaching flange 35 which is shouldered as at 35^a, to receive the lower flange portion of the exhaust pipe 45 tip 27; the latter being suitably bolted or otherwise secured to the exhaust pipe. The exhaust pipe tip 27 is shown in the form of a cored block to provide the restricted 50 openings or nozzles 36, 36 and 37, 37. The passages in the exhaust tip 27 are flared toward the bottom and thus provide an intermediate bridge 38 adapted to extend across the partitions 29, 29, see Figure 4. The 55 bridge 38 tapers toward the bottom, with two of its sides given a greater bevel or taper as shown in Figure 3, thereby providing the inverted cone-shape in cross-section, whereby the steam passing through exhaust passage 26 (which extends transversely of the exhaust 60 pipe) is split or divided and caused to discharge through the nozzles 36, 36, namely into the two steam jets shown at 39, 39 in Figure 1, which discharge more or less centrally into the smoke stack and completely 65 fill the same; while the steam issuing from

the openings or nozzles 37, 37 will be discharged in the form of the jets 40, 40, shown in Figure 2, and also in a manner to completely fill the smoke stack, with the result that the exhaust steam will induce proper 70 draught through the fire tubes of the boiler.

With my improved exhaust pipe, it is apparent that the exhaust steam may freely flow from the exhaust passages of the cylinder saddle; the exhaust steam, in the particular illustration, from the steam passage 18 passing up into the exhaust passage 26 of the exhaust pipe and being divided into separate jets in the upper end of the exhaust pipe by suitable means, as for example by 80 the bridge portion 38 of the exhaust tip or nozzle; while the exhaust steam from the passage 19 is discharged into the passage 32 and by reason of the partitions and walls is caused to flow into the two passages 33 at 85 the upper end of the exhaust pipe and thence through the nozzles 37, 37 of the exhaust pipe tip. With my improved exhaust pipe, the steam is not only permitted free flow through the exhaust pipe, but possibility of 90 the exhaust steam from the cylinder on one side of the locomotive to "back up" into the exhaust steam passages from the cylinder on the opposite side of the locomotive is made absolutely impossible, as there is no 95 communication between the exhaust passage 26 and the exhaust passage 32 and its branches as is clearly evident from the construction shown. This construction, therefore, eliminates all possibility of the creation 100 of back pressure in the opposite exhaust channels.

I am aware that exhaust pipes have been used which eliminate the back pressure due to the steam "backing up" in the opposite exhaust channels, but these exhaust pipes are of such construction that the exhaust steam does not properly fill the smoke stack and as a result the draft created was not sufficient to enable the boiler to produce the steam necessary to operate the locomotive efficiently or to full capacity.

The exhaust pipe most commonly used is constructed with a partition wall which keeps the exhaust steam of each cylinder 115 separated merely to a point midway of the exhaust pipe and the exhaust pipe above the partition has a single passage which is reduced toward the top for the purpose of imparting force and velocity to the exhaust 120 steam for the purpose of inducing the draft. This reduction or narrowing of the passage, however, causes the exhaust steam to "back up" into the opposite exhaust channel and thence to the piston on that side of the locomotive, where it interferes with or reduces the effective force.

With my improved exhaust pipe, however, the exhaust steam from one cylinder is not permitted to "back up" into the exhaust 130

channel and passages of the opposite cylinder, but on the other hand is completely conducted out through the smoke stack in a central manner.

I have shown and described the passage 26 as receiving the exhaust steam from the channel 18 and passage 32 as receiving the steam from channel 19, but it is apparent that the exhaust pipe may be turned so as 10 to reverse this condition; and while my exhaust pipe has been shown conducting the exhaust steam through the exhaust pipe tip by two separate passages for either end of each cylinder, it is evident that any number 15 of passages or nozzles may be employed; and that the division of the steam passing upward through passage 26 may be differently accomplished at the upper end of the exhaust pipe from that disclosed, without, however, departing from the spirit of my invention which has been described in terms of description and not in terms of limitation, 20 as structural modifications are possible.

What I claim is:—

25 1. An exhaust pipe provided with partitions whereby the pipe interior is divided into a plurality of independent passages throughout the length of the pipe, said partitions being so formed that one of said passages terminates in an opening disposed transversely of the upper end of the pipe while the other passage terminates in openings disposed on opposite sides of the median line of the opening of said first 30 mentioned passage.

2. An exhaust pipe provided with partitions extending from bottom to top whereby the pipe is divided into a plurality of independent passages extending throughout the length of the pipe, said partitions being so formed as to have one passage extend diametrically of the pipe while the other passage is bisected and terminates in an opening on each side of the median line 40 of the first mentioned passage, and a removable tip provided with tapered openings, one pair of openings communicating with each passage in the pipe whereby the exhaust steam from each passage is dis-

charged in the form of two oppositely disposed jets. 50

3. An exhaust pipe provided with partitions whereby the pipe is divided into separate passages, each passage being adapted to receive the exhaust steam from a different cylinder, and a tip provided with a plurality of separate tapered passages, the oppositely disposed tip passages exhausting the steam from a single pipe passage whereby the steam flowing through the passages 55 of the pipe is simultaneously discharged in the form of two oppositely disposed jets. 60

4. An exhaust pipe provided with intersecting walls whereby a plurality of independent passages throughout the pipe are 65 provided from top to bottom, terminating at top in discharge openings, the opening of one passage being disposed transversely of the pipe and restricted at an intermediate point while the other openings are 70 disposed on opposite sides of the restricted portion of the first mentioned opening.

5. An exhaust pipe provided with intersecting walls and partitions whereby a plurality of independent passages throughout 75 the pipe are provided, terminating at top in discharge openings, the opening of one passage being disposed along the transverse axis of the upper end of the pipe while the other openings are disposed on 80 opposite sides of the first mentioned opening.

6. An exhaust pipe provided with a plurality of independent passages extending throughout the length of the pipe, the passages at the base of the pipe being arranged parallel with each other and terminating at the upper end of the pipe in orifices disposed along the transverse axis of the pipe 85 and on opposite sides of said transverse axis, and a tip provided with a plurality of tapered openings, one pair of openings communicating with each pipe passage whereby the exhaust steam from each passage is discharged in the form of two 90 oppositely disposed jets. 95
